UNITED STATES PATENT OFFICE.

RAYMOND E. CRANE AND OSCAR J. BACKUS, OF NEWARK, NEW JERSEY.

BASIN AND BATH SUPPLY FITTING.

991,703.

Specification of Letters Patent.

Patented May 9, 1911.

Application filed April 19, 1906. Serial No. 312,555.

To all whom it may concern:

Be it known that we, RAYMOND E. CRANE and OSCAR J. BACKUS, citizens of the United States, residing at Newark, in the county of 5 Essex and State of New Jersey, have invented certain new and useful Improvements in Basin and Bath Supply Fittings, of which the following is a specification.

Our invention relates to improvements in 10 basin and tub supplies in which both the hot and cold water are supplied from a single fixture.

The objects of our invention are to provide a suitable and compact device which 15 shall occupy as little space as possible on the basin slab or the tub rim, and which will allow the base joint between the fixture and the basin slab to be cleaned more easily than usual. Said objects are accomplished in the 20 manner shown in the accompanying drawing, in which a front view of the device is shown embodying a waste operating device in connection therewith. The part below the top of the slab is shown partly in section, 25 otherwise the figure is a front view.

Referring to the accompanying drawing:— the supply channels B and C are contained in the round stem A which is threaded at the bottom so that the locknuts N and P will 30 draw the base shoulder R tightly against the slab M.

The fixture is provided with channels connecting inlets B and C with spout S. The 35 valves D and E control the flow from the inlets B and C into spout S. F and G are the valve stems by means of which valves D and E are operated.

The lever H, having a lifting arm I cast integral therewith, controls the waste of the 40 basin to which it is fitted as rod K is connected to the waste plug. Rod K is connected to arm I by means of pin J.

It will be seen that our construction embodies two valve stems that are connected to 45 a single base post, said stems being placed at an upward angle from the slab. This construction is much superior to the common style where the valve stems are horizontal or vertical as in either case the accessibility 50 of the base joint with the slab and also the base post is interfered with by either the handles of the cocks, or the horizontal parts thereof, or both. Our construction has an

especial advantage in a corner lavatory where the backs make very little room for 55 the cock and it is desirable to have it as small as possible.

It will be noted that the stem A, which incloses the supply channels B and C for the hot and cold water, depends from the base 60 or shoulder R of the fixture, and that it incloses said supply channels at the point where it passes through the slab. The valve stems F and G extend upward and outward from the supporting post or standard in such 65 a way as to form the upper branches or arms of the Y-shaped fixture, the main portion of the Y being constituted by the upright post itself.

We believe that our Y-shaped cock is the 70 most compact construction on the market as well as the most accessible. We also believe that it has sanitary features which are novel in this kind of a fixture.

We claim the following as new and desire 75 to secure Letters Patent thereon.

1. The combination with a slab, of a Y-shaped basin or bath supply fixture comprising a hollow upright post or standard having a base resting on the slab, supply channels for the hot and cold water passing through the slab under said base and into said post or standard, and valves to control said supply channels and having stems extending upward and outward from said post 80 or standard and constituting the upper arms or branches of the Y.

2. The combination with a slab, of a Y-shaped basin or bath supply fixture comprising a hollow upright post or standard having a base resting on the slab, a stem depending from said base and passing through the slab, supply channels for the hot and cold water, inclosed by said stem and passing into the fixture, and valves to control said 90 passages, having stems extending upward and outward from said post or standard and forming the upper arms or branches of the Y.

In testimony whereof we affix our signatures in presence of two witnesses.

R. E. CRANE.

OSCAR J. BACKUS.
